(57) **CLAIM**

I claim the ornamental design for a toy for animals, as shown and described.

DESCRIPTION

FIG. 1 is a perspective view of my new design for a toy for animals;

FIG. 2 is a front view thereof;

FIG. 3 is a top view thereof;

FIG. 4 is a right side view thereof;

FIG. 5 is a left side view thereof;

FIG. 6 is a rear view thereof; and,

FIG. 7 is a bottom view thereof.

The toy for animals has the shape and appearance of a rugby ball with a handle.
